CLAIM

The ornamental design for an adaptor with ball as shown and described.

DESCRIPTION

FIG. 1 is a top perspective view of an adaptor with ball showing our new design;

FIG. 2 is a bottom perspective view thereof;

FIG. 3 is a first side view thereof;

FIG. 4 is a second side view thereof;

FIG. 5 is a top view thereof;

FIG. 6 is a bottom view thereof;

FIG. 7 is a third side view thereof;

FIG. 8 is a fourth side view thereof;

FIG. 9 is a top perspective view of another embodiment of an adaptor with ball showing our new design;

FIG. 10 is a bottom perspective view thereof;

FIG. 11 is a first side view thereof;

FIG. 12 is a second side view thereof;

FIG. 13 is a top view thereof;

FIG. 14 is a bottom view thereof;

FIG. 15 is a third side view thereof; and,

FIG. 16 is a fourth side view thereof.

The broken lines in the drawings are included to show portions of the adaptor with ball that form no part of the claimed design.

1 Claim, 6 Drawing Sheets
